UNITED STATES PATENT OFFICE.

FREDERIC LARSON, OF ROYALTON, MINNESOTA.

BENCH-DOG.

SPECIFICATION forming part of Letters Patent No. 378,890, dated March 6, 1888.

Application filed December 27, 1887. Serial No. 259,063. (No model.)

To all whom it may concern:

Be it known that I, FREDERIC LARSON, a citizen of the United States of America, residing at Royalton, in the county of Morrison and State of Minnesota, have invented certain new and useful Improvements in Bench-Dogs, of which the following is a specification, reference being had therein to the accompanying drawings.

10 My invention relates to improvements in bench-dogs for the use of carpenters, joiners, &c., in which the longitudinally-reciprocating dog is provided with rack-teeth to engage with a toothed lever; and the objects of my improvement are, first, to provide a device of this nature in which the sliding dog is inclosed and protected and guided by a frame extending substantially its whole length; second, to afford facilities for securing the device at both 15 ends to the top of a bench, and producing it at little expense. I attain these objects by the construction illustrated in the accompanying drawings, in which—

Figure 1 is a perspective view of a bench-dog constructed in accordance with my invention and shown connected to a bench. Fig. 2 is a top view of the same with the cap-plate removed. Fig. 3 is a longitudinal section of the same taken on the long axis of the dog.

20 In said drawings, A represents a flat metallic frame having its edge a^1 turned up to support and guide the dog B substantially the whole length thereof against the pressure exerted upon it by the segmental toothed lever C. The frame A has at its ends lugs a^2 , that support the dog B against lateral pressure, and said lugs are perforated to receive rivets or screws to fasten the cap-plate A ^{2} to the bottom frame, A. The dog B is in the form of a 25 rack having teeth b formed on one of its edges, with which mesh the teeth c , formed around the segmental periphery of the hand-lever C, pivoted at c^2 to the frame A and its cap-plate.

To give freedom of play to the dog and its 30 operating-lever, the cap-plate is supported upon cylindrical lugs a^3 , projecting up from

the frame A between the rack and lever, and one of said lugs serves as a journal for the pawl d , that is there located in proper position to engage with the teeth on the periphery of the 35 lever C, and a spring may be made to press against the back of said pawl. The lugs a^3 are perforated to receive rivets to secure the cap-plate to the frame A at these points. To retain the bench-dog connected with a bench, as 40 at E, it is provided at each end with a downwardly-projecting pin, a^4 , preferably slightly inclined rearwardly to enter holes e , correspondingly bored in the top surface of the bench. The forward end of the dog is curved 45 up at an acute angle to its body at b^2 , to properly be forced into engagement with the end of a small thin board, as f , and elevate its top surface above that of the cap-plate. The opposite end of said board is retained by a vertically-adjustable dog, g , of any suitable form.

Having now fully described my invention, I claim—

1. A bench-dog consisting of the frame A, having lugs at each end, a turned-up edge between said lugs, and a pendent pin at each end, with a dog having teeth on one of its edges, a toothed segmental lever, a pawl pivoted to the frame A, and a cap-plate extending the whole length of said frame, substantially as and for 70 the purpose described.

2. The combination of the frame A, having the turned-up edge a the whole length thereof, the cap-plate secured to said frame, a toothed segmental lever pivoted to the frame and cap-plate, a pawl pivoted to said frame and adapted to engage with the teeth of the lever, and a dog having teeth on one of its edges and its forward end curved up at an acute angle to its body, substantially as and for the purpose described.

In testimony whereof I affix my signature in presence of two witnesses.

FREDERIC LARSON.
